UNITED STATES PATENT OFFICE.

CHARLES GUSHWA, OF ELKHART, INDIANA.

WIRE-FENCE TIGHTENER.

1,423,211.

Specification of Letters Patent. Patented July 18, 1922.

Application filed April 10, 1922. Serial No. 551,431.

To all whom it may concern:

Be it known that I, CHARLES GUSHWA, a citizen of the United States, residing at Elkhart, in the county of Elkhart and State 5 of Indiana, have invented certain new and useful Improvements in Wire-Fence Tighteners, of which the following is a specification, reference being had to the accompanying drawings.

10 This invention relates to wire tightening devices, and more particularly to a wire tightening device for wire fences.

An object of the invention is to provide a device of this character capable of being 15 attached to the wire at any point to eliminate the sagging of the wire and render the same taut.

Another object of the invention is to provide a device of this character which is 20 compact in form, so that any number of the devices may be applied to the section of a fence to tighten all portions of the wire without requiring the wire to be disconnected from the fence posts.

25 It is a further object of the invention to provide a device of this character adapted to substantially form a crimp in the wire, said device being applied by means of an implement, capable of being readily detached after the application of the device to the wire.

It is a still further object of the invention to provide a device of this character which can be stamped from a small quantity of sheet metal.

With these and other objects in view, the invention consists in the improved construction and arrangement of parts to be hereinafter more particularly described, 40 fully claimed and illustrated in the accompanying drawings, in which:

Figure 1 is a fragmentary elevation of a fence section showing the invention applied;

45 Figure 2 is a perspective view of the tightener;

Figure 3 is a rear elevation; and

Figure 4 is a perspective view of the tool used in applying the tightener.

50 Referring to the drawings, 5 designates the body member of the tightener, said body member consisting of a sheet metal blank substantially triangular in shape. It is of course obvious that the device may be 55 made square or other shapes if desired,

without interfering with the application or operation of the tightener.

The corner 6 of the body member is provided with an extension 7, said extending being extended back upon the face 8 of the body member to provide a hook 9, the hook extending toward the central portion of the body member, the extremity of the extension 7 being tapered to permit unobstructed movement of the wire thereover. Projecting from the opposite corner 10 of the plate is an extension 11, similar to the extension 7, the extremity of the extension 11 being tapered to permit unobstructed movement of the wire, similar to the extremity of the extension 7. The extension 11 is intended to be extended back upon the face 8 of the body member and toward the center of the body member to provide a hook. It will be noted that after the hook 75 is formed, that the edge 12 of the extension 7 and the edge 13 of the extension 11 extend slightly above the edge 14 of the body member, so as to cause said edge to substantially bite into the wire without interference from the body member.

The remaining corner of the body member is removed to provide a relatively straight edge 15 which is disposed in parallel relation to the edge 14 of the body member. A finger 16 is struck from the end portion 15, the finger 16 being disposed normally in the plane of the face 8 of the body member. The portions 17 and 18 on each side of the finger 16 are extended outwardly beyond the opposite face of the body member substantially in alignment with each other, and cooperate with the finger to provide a wire receiving recess 19. The central portion of the body member 5 95 is provided with a rectangular opening 20 adapted to receive means for applying the device to the wire.

To apply the device to a slack wire, a novel tool 21 is provided, said tool having 100 a square shank 22, the extremity of which is adapted to enter the opening 20, the opposite end of the shank being constructed to enter the socket of a conventional form of brace. To tighten the wire, the edge 13 of the hook 105 formed by the extension 11 is engaged with a portion of the wire, the wire being passed over the face 8 of the body member and into the recess 19 provided in the finger 16 and portions 17 and 18 of the plate. The body 110

member is then rotated through the medium of the tool 21 and brace, so as to move the hook formed by the extension 7 downwardly and beneath the wire, thereby causing the 5 wire to engage the edge 12 of said hook. This operation may be accomplished by an oscillating movement of the brace to first engage one hook and then the other. It is not necessary to rotate the implement. After 10 the wire engages the hook formed by the extension 7, a crimp is formed in the wire which draws the same taut between the fence posts. If one tightening operation is not sufficient to properly tighten the wire, another 15 tightening device may be applied in spaced relation to the first one. As these devices are small, any number may be applied to the fence to strengthen the same without increasing the weight of the fence 20 or affecting its appearance.

From the foregoing it will be readily seen that this invention provides a novel wire 25 tightener for fences capable of being readily applied to any type of wire fence by anyone, without disconnecting the fence from the 30 posts, and all of these features are possessed by a device that can be stamped in large 35 numbers from a small quantity of sheet metal.

39 What is claimed is:—

1. A wire tightener consisting of a plate having an opening in its central portion for the reception of a tool, extensions carried by certain corners of said plate, said extensions being extended back upon the plate to

provide hooks, and fingers projecting from the end portion of the plate remote from the hooks, said fingers coacting with each other to provide a recess.

2. A wire tightener consisting of a substantially triangular plate having a central opening for the reception of a rotatable tool, extensions carried by two of the corners of the plate, said extensions being extended back upon the plate to provide hooks, the remaining corner of the plate having a finger struck therefrom, the portions of the last mentioned corner adjacent the finger being extended outwardly and coacting with the finger to provide a recess for the reception of the wire. 40

3. A wire tightener consisting of a substantially triangular plate, two of the corners of the plate having outwardly projecting extensions, said extensions being extended back upon said body member to provide hooks, a portion of each hook extending beyond one edge of the plate, the opposite corner of the plate having a finger struck therefrom, said finger cooperating with the portions of the last mentioned corner adjacent the finger to provide a recess for the reception of the wire, said recess cooperating with the hooks to substantially form a V-shaped crimp in the wire upon rotation of 60 the body member upon the wire. 65

In testimony whereof I hereunto affix my signature.

CHARLES GUSHWA.
